UNITED STATES PATENT OFFICE.

HENRY CARTER OSTERBIND, OF RICHMOND, VIRGINIA.

MACHINE FOR ROLLING HORSESHOE-BLANK BARS.

SPECIFICATION forming part of Letters Patent No. 349,950, dated September 28, 1886.

Application filed August 3, 1886. Serial No. 209,853. (No model.)

To all whom it may concern:

Be it known that I, HENRY CARTER OSTERBIND, of Richmond, in the county of Henrico and State of Virginia, have invented certain new and useful Improvements in Machines for Manufacturing Horseshoe-Blanks, of which the following is a specification, reference being had to the accompanying drawings, in which—

Figure 1 is an end view of my improved machine. Fig. 2 is a side view. Fig. 3 is a detached view of the bottom roller. Fig. 4 is a detached view of the swaging-roller. Fig. 5 is a section of the heel portion of a blank to be formed. Fig. 6 is a section through the creased part of the same; and Fig. 7 is a view showing a formal modification of the creasing and swaging rollers where they come in contact.

The object of my invention is to provide a machine for rolling out a series of horseshoe-blanks from a suitable bar for the purpose, and in the same rolling operation to do three things—to wit, first, to crease the blank; second, to thin it and bevel it without narrowing between the heel ends and on the opposite side to where the creases are; and, third, to swage the heel ends. This, as generally stated above, has been done before; but my machine is of peculiar construction for doing it advantageously and without some of the difficulties and imperfections that have heretofore existed.

Referring to the letters upon the accompanying drawings, A indicates the main frame or housings, which may be such as illustrated, or of any other ordinary or suitable character.

B is a horizontal roller-shaft, mounted in ordinary journals in the main frame and carrying pinion C, collar D, which may be cast integral with the shaft, bottom roller, E, and bevelled pinion F.

G indicates another shaft in suitable bearings in the main frame, but inclined with respect to the shaft B, as illustrated. This shaft G carries the pinion H, collar I, and creasing-roller K.

L is a shaft perpendicular to the shaft B, carrying bevelled pinion M and heel-swaging roller N.

O indicates a front guide, provided with a feed-opening, P, with a flaring mouth, as usual.

Q indicates a rear or delivery guide, of usual construction.

The bottom roller, E, is provided with a collar, R, for forming the front edge of the shoe. The surface S of this roller is provided with depressions T to form the heel portions of the blanks. In this instance three are shown; but more or a less number might be provided, according to the size of the roll. These depressions permit the metal while being swaged at the heel portions of the blanks by the operation of all the rollers to thicken up, so that the desired nearly square form at the heels is attained. The general surface S of the bottom roller, E, it will be observed, is inclined inward toward the collar R. The object of this is to properly bevel the top part of the blank, which corresponds to the part of the shoe placed against the hoof of an animal. The creasing-roller K is inclined, like the shaft G, with respect to the bottom roller, E, and is arranged so as to crease the blank upon the edge next to the collar R. The result is as the collar R is integral with the roller E the creasing is done where there is no joint for finning of the blank at the angle, which should be clean and sharp on the opposite side to where the creases are made. The swaging-roller N is provided with projections U, adapted to do the whole work upon the edge of the bar opposite to where the creases are made. These projections correspond in position and in operation come opposite to the depressions T in the surface of the roller E, and serve to form the nearly square heel portions of the blank. In the present instance three of these projections are shown; but more or a less a number might be employed, according to the size of the swaging-roller. This roller is bevelled at V on its upper side, so as to be parallel with the periphery of the creasing-roller, which impinges against it.

Instead of beveling the swaging-roller at V, it might be made plain and horizontal on its upper surface, and the creasing-roller might be formed to fit it, as indicated in Fig. 7, the object being to use an inclined shaft and creasing-roller, but to get a close joint between the creasing and swaging rollers where they contact. It may be done in either of the ways mentioned, though I prefer to use a bevel on the top of the swaging-roller. Besides these peculiarities of construction, the roller N is

provided with an irregular surface of projections and depressions, W, immediately beneath the bevel V, adapted to cause it to closely fit the irregular or eccentric surface S 5 of the bottom roller, E. The concentric part X of the roller N bears against the side of the roller E and forms a tight joint. It will be seen that the collars D and I, being cast integral with the shafts B and G or fixed solidly 10 thereon, and bearing against each other at their sides, as illustrated, serve to transfer the lateral strain from roller E to shaft G when the heel portions of the blanks are being swaged, so that the resistance of the fastenings of both shafts is availed of equally to support that strain. It will also be seen that when 15 the creasing is being done there is a great strain exerted between the collar R and the working creaser which would tend to separate 20 them. This strain is also resisted by the collars D and I.

It will be desirable in practice to make the rollers E, K, and N in sets corresponding in size to a given size and length of shoe-blank. 25 I provide for taking off these rollers and putting on other sets of different sizes by making the bearings of the shaft G adjustable up and down, as usual.

One advantage of having the inclined shaft 30 is that when the sets of rollers are changed the inclined shaft can be adjusted up or down,

and the pinions C and H can be shifted longitudinally upon their shafts where they are keyed, so that they will properly engage when the shafts may be at varying distances apart. 35 Therefore a single pair of pinions will serve for different sets of rolls. The degree of incline of the shaft G should be such as to secure the proper bevel of the blank, and at the same time the proper creasing.

Having thus described my improvements, what I claim to be new, and desire to secure by Letters Patent, is—

1. The combination, with the horizontal, inclined, and vertical roller-shafts, of the adjustable pinions C and H, the collars D and I, and the bottom roller, swaging-roller, and creasing-roller, constructed and operating together substantially as set forth. 45

2. The combination of the bottom roller, E, 50 provided with collar R, its surface S having the heel-forming depressions T, the inclined creasing-roller K, and the swaging-roller N, having projections U, irregular lower surface, W, and concentric bearing part X, substantially as set forth. 55

In testimony whereof I have hereunto subscribed my name.

HENRY CARTER OSTERBIND.
